UNITED STATES PATENT OFFICE.

ERNEST CANTELO WHITE, OF NEW YORK, N. Y., ASSIGNOR TO DUPLEXALITE CORPORATION, OF NEW YORK, N. Y., A CORPORATION OF NEW YORK.

GRIP-FITTING FOR ELECTRIC CORD.

1,342,787.

Specification of Letters Patent. Patented June 8, 1920.

Application filed August 26, 1918. Serial No. 251,395.

To all whom it may concern:

Be it known that I, ERNEST CANTELO WHITE, a citizen of the United States, residing in the borough of Manhattan, of the 5 city of New York, in the State of New York, have invented certain new and useful Improvements in Grip-Fittings for Electric Cords, of which the following is a specification, reference being had to the accompanying drawing, forming a part hereof.

This invention relates to the means by which the physical connection between an electric lighting cable and the lighting fixture at its lower end and between the cable 15 and the canopy or its equivalent at the upper end is effected. The purpose is to provide an inexpensive means for causing the cable to be gripped tightly at the upper end of the lighting fixture or at the lower end of 20 the canopy or its equivalent, as the case may be. Heretofore, a split, rigid ring, of hard material, has been formed and made to encircle the cable, being clamped thereon by a sleeve which forms a part of the fixture, 25 either the lighting fixture or the canopy, as the case may be. Such split ring, of unyielding material, must be fitted approximately to the cable and, in quantities, involves a considerable expense in manufacture and application. In accordance with 30 the present invention, there is provided a ring of yielding material which is squeezed between the cable and a part of the fixture. The invention will be more fully explained 35 hereinafter with reference to the accompanying drawing in which it is illustrated and in which—

Figure 1 is a view, partly in vertical section and partly in elevation, of a lighting fixture, including the canopy and the lamp with its attachments and illustrating the application of the invention in connection with the lighting cable.

Figs. 2, 3 and 4 are detail views showing 40 different forms of the elastic ring referred to hereinafter.

Fig. 5 is a detail view in section illustrating a slightly different embodiment of the invention from that shown in Fig. 1.

50 The improved supporting device can be applied wherever a cable is connected to a metal fixture, whether it be the canopy, through which the fixture is suspended from the ceiling, or the lighting fixture itself, including the lamp only, or the lamp and its

appurtenances. It comprises a coupling member a , a' , a^2 , which is secured to the lamp or the canopy or other part of the fixture in any convenient manner. As shown in the upper part of Fig. 1, the coupling member a is secured to the usual canopy b by a nut a^3 which engages the threaded portion of the coupling member within the canopy. As shown in the lower part of Fig. 1, the coupling member a' is threaded directly into the lamp socket c . The coupling member a^2 , shown in Fig. 5, is also adapted to be threaded into the lamp socket or into a retaining nut as the case may be.

Another member of the supporting device is a sleeve d , d' , d^2 adapted to crowd the gripping ring hereinafter mentioned into close contact with the cable and adapted to be drawn toward the coupling member a , a' , a^2 , being preferably tapered internally. As shown in Fig. 1, the sleeve is formed with a narrow lip d^3 , adapted to be engaged by an internal lip e' of a nut e which is threaded at e^2 upon the corresponding threaded portion of the coupling member a , a' . As shown in Fig. 5, the tapered sleeve d^2 is itself threaded, as at d^4 , directly upon the threaded portion of the coupling member a^2 . The latter construction involves a smaller number of parts, but it has, as compared with the construction shown in Fig. 1, the disadvantage of requiring rotation of the sleeve d^2 with respect to the coupling member a^2 .

Finally, the device includes a yielding, 90 resilient clamping ring, fitting rather snugly about the cable g , and placed within the internally tapered sleeve d , d' , d^2 , so that it is caused to grip the cable tightly and is forced more closely into contact with the 95 cable by any relative movement of the internally tapered sleeve and cable caused by the weight of the suspended parts. Preferably the gripping ring is of soft rubber and is circular in cross section, as shown at 100 f in Fig. 2, but it might be of rubber and rectangular in cross section, as shown at f' in Fig. 3, or it might be of helically wound wire, as shown at f^2 in Fig. 4. Obviously, it might be made of other materials or have 105 other shapes in cross section suited to the particular conditions of use. In any case, the elastic, yielding gripping ring is caused by the internally tapered sleeve to grip the cable g tightly, and the device will be found 110

2
to be of special advantage in connection with cables provided with jute laterals g' , which are gripped tightly by the action of the gripping ring and take the strain due to the weight of the suspended parts, before the copper conductors stretch.

In assembling the supporting device, fixture and cable, the internally tapered sleeve is inserted in the nut (referring to the construction shown in Fig. 1) and the two are slipped upon the cable with the open end toward the end of the cable. The gripping ring is then slipped upon the cable and the cable is passed through the coupling member a, a' , and spliced to the lead or secured to the lamp socket in the usual manner. Finally, the internally tapered sleeve, nut and gripping ring are slipped upon the cable to a point near the coupling member, the gripping ring is crowded into the internally tapered sleeve and the latter is secured to the coupling member by the nut, the gripping ring being thereby merely prevented from escaping from the internally tapered sleeve or crowded farther therein as the case may be. The mode of use of the form of the device shown in Fig. 5 will be readily understood without further explanation than to state that the coupling member must be rotated relatively to the internally tapered sleeve, to bring the two into engagement. As rotation of the internally tapered sleeve might be injurious to the gripping ring, the construction shown in Fig. 1 is therefore preferred because the rotation of parts in contact with the cable is not required.

I claim as my invention:

1. A grip fitting for electric cords including a yielding, elastic gripping ring

having capacity for rolling movement on the cable and adapted to encircle the lighting cable snugly, a tapered sleeve encircling the gripping ring and crowding it into contact with the cable upon relative movement between the cable and sleeve thereby causing the ring to tend to roll on the cable and means independent functionally of said ring to secure the sleeve to the fixture and prevent the escape of the gripping ring.

2. A grip fitting for electric cords including a yielding, elastic gripping ring having capacity for rolling movement on the cable and adapted to encircle the lighting cable snugly, a coupling member independent functionally of said ring secured to the fixture, a tapered sleeve encircling the gripping ring and crowding it into contact with the cable upon relative movement between the cable and sleeve thereby causing the ring to tend to roll on the cable, and means to secure the sleeve to the coupling member.

3. A grip fitting for electric cords including a yielding, elastic gripping ring having capacity for rolling movement on the cable and adapted to encircle the lighting cable snugly, a coupling member independent functionally of said ring secured to the fixture, a tapered sleeve encircling the gripping ring and crowding it into contact with the cable upon relative movement between the cable and sleeve thereby causing the ring to tend to roll on the cable, and a nut engaging the sleeve and the coupling member to draw the sleeve toward the coupling member.

This specification signed this 21st day of August, A. D. 1918.

ERNEST CANTELO WHITE.
